UNITED STATES PATENT OFFICE.

IRVING R. LEDERER, OF PROVIDENCE RHODE ISLAND.

GARMENT-HOLDER.

1,288,059.

Specification of Letters Patent. Patented Dec. 17, 1918.

Application filed June 5, 1918. Serial No. 238,289.

To all whom it may concern:

Be it known that I, IRVING R. LEDERER, a citizen of the United States, and resident of the city of Providence, in the county of 5 Providence and State of Rhode Island, have invented certain new and useful Improvements in Garment-Holders, of which the following is a specification.

This invention relates to a garment holder, 10 more particularly used for connecting together the opposite edges of a soft collar to prevent the same from spreading, and this invention has for its object to provide a bar on the under side of which is mounted 15 a pair of spring actuated jaw members adapted to engage the adjacent edges of a collar to retain them in a given position relative to each other.

With these and other objects in view, the 20 invention consists of certain novel features of construction, as will be more fully described, and particularly pointed out in the appended claim.

In the accompanying drawings:

25 Fig. 1— is a front view of a collar showing my improved clamping bar as retaining the collar in adjusted position.

Fig. 2— is a view showing the blank as 30 cut from sheet stock from which the bar is formed.

Fig. 3— is a perspective view showing the blank as bent up into a channel-bar form.

Fig. 4— is a central sectional edge view 35 of the bar, showing the edge flanges as cut away near the opposite ends thereof.

Fig. 5— is a detail in perspective of the clamping member.

Fig. 6— is a detail of the one piece sheet metal spring.

40 Fig. 7— is a central sectional edge view showing the clamp and spring assembled in the bar.

Fig. 8— is a plan view showing the under 45 side of the bar with the parts mounted therein.

Referring to the drawings, 10 designates the bar member which is preferably blanked out of sheet stock in the form illustrated in Fig. 2 having ears 11 formed integral 50 with the edge thereof. The next operation after cutting out this blank is to swage or draw the same up into substantially the same form illustrated in Fig. 3, which is that of a trough or channel shape having its 55 opposite edges 12 turned up to form side flanges, the ends 13 being also turned up

to form biting lips for engaging the fabric. In order to obtain a more perfect binding and gripping effect I have cut away the edges of these flanges as at 14 near the 60 opposite ends of the bar.

The gripping member 15 is also preferably blanked out of sheet stock having its end 16 turned inwardly and preferably notched as at 17 to form teeth for better 65 gripping the fabric of the garment. The opposite end of this member 18 is shaped to form an operating handle. Small pintles 19 are formed integral with the opposite edges of this member, which pintles are 70 adapted to pass through the eyes 20 in the ears 11 for the purpose of pivoting these members thereto, one at each end of the bar, said members extending in opposite directions with the biting ends adapted to co-operate with the upturned end lip 13 of the bar. 75

In order to provide the necessary gripping tension for these clamping members I have formed a sheet metal spring 21 of a width adapted to loosely lie in the channel 80 between the side flanges 12, its ends 22 being turned outwardly so as to engage the under side of each of the opposite clamping members, to normally hold these biting ends 85 closed against the inner face of the bar.

By this construction the spring is retained in position in the back of the bar without fastening and a single spring member formed of sheet metal serves to act upon and operate both of the clamping members, 90 which members are independently operable.

The device is extremely simple and practical in construction and is adapted to be most readily attached to the opposite adjacent edges of the collar to hold them firmly 95 in adjusted position and by this construction the face of the bar may be left entirely plain or made as ornamental as desired rendering the device handsome and attractive in appearance. 100

The foregoing description is directed solely toward the construction illustrated, but I desire it to be understood that I reserve the privilege of resorting to all the mechanical changes to which the device is 105 susceptible, the invention being defined and limited only by the terms of the appended claim.

I claim:

A collar holder comprising a channel bar 110 having upturned and biting lips, side flanges on said bar with two pairs of pivot ears,

formed thereon, oppositely extending clamping members, one pivoted between each pair of ears and facing in opposite directions forming independently operable jaws, each 5 coöperating with its end lip, and a flat spring in said channel loosely held between said flanges having opposite upturned ends

yieldably engaging both of said members to hold them normally closed against the bar.

In testimony whereof I affix my signature 10 in presence of a witness.

IRVING R. LEDERER.

Witness:

HOWARD E. BARLOW.
